UNITED STATES PATENT OFFICE.

JOHNSON LETSON, OF NEW BRUNSWICK, NEW JERSEY.

IMPROVEMENT IN WATER-PROOF SHOES.

Specification forming part of Letters Patent No. 59,419, dated November 6, 1866.

To all whom it may concern:

Be it known that I, JOHNSON LETSON, of New Brunswick, in the county of Middlesex and State of New Jersey, have invented certain new and useful Improvements in Rubber Boots and Shoes; and I hereby declare the following to be a full, clear, and exact description of the same, reference being had to the accompanying drawing, in which is represented, in vertical section, a rubber overshoe constructed in accordance with my invention.

My invention relates to that class of rubber shoes in which an upper of cloth, felt, or other suitable fabric is combined with a rubber foxing and sole; and its object is to produce a shoe which, while water-proof or impervious to moisture at those points where the shoe is most likely to become wet, shall yet be ventilating and afford perfect opportunity for the insensible moisture and perspiration from the foot to pass off. The improvements therefore which I have made the subject of this application have relation to the construction of the upper—the only part of the shoe which can be made ventilating without detracting from its water-proof properties, and they consist in interposing between the cloth vamp and inner lining a sheeting of rubber under such an arrangement that the air is free to circulate between the lining and the rubber, and also, if desired, between the vamp and the rubber, while, at the same time, the upper is still kept water-proof, and prevents the water or moisture from reaching the foot.

In order to effect these improvements, I take, before the shoe is put together, the cloth upper and attach to its under side a thin sheet of rubber, either by means of cements or by pressure between calenders. This sheeting need not be spread over the whole surface of the vamp, but may only extend up sufficiently high to cover that part of the upper which is liable to become wet. The vamp thus prepared is attached to the lining, forming the upper, which is secured to the other parts of the shoe in the usual way. The woolen or felt lining, however, is not cemented to the water-proof vamp, but is secured to it only at its edges, the rest of the lining being perfectly loose, and detached from the sheet of rubber interposed between it and the vamp. The effect of this arrangement, is that the air is

free to circulate between the lining and vamp, and a medium is thus furnished by which the moisture from the foot is carried off. The same process may be employed to make the quarter water-proof, the lining remaining detached from the water-proof quarter.

In order to still further promote the ventilating of the shoe, the rubber sheet which is interposed between the lining and the vamp need not be cemented or calendered to the vamp. It will be sufficient to have it secured at its lower edge to the vamp or foxing, leaving the other part of the sheet entirely loose and separate from the vamp. The air under this arrangement can circulate as well between the rubber sheeting and the lining, the three parts which compose the upper—viz., the cloth vamp, sheeting of rubber, and lining—being loose and unattached to each other except at their lower edges, while at the same time the rubber sheeting will effectually keep the water from penetrating to the foot.

Instead of the sheet of rubber, a piece of cloth or stockinet, or other textile or woven fabric, coated on either one or on both sides with rubber, may be used with equally good effect.

To enable others to understand and use my invention, I will now proceed to describe one method in which the same may be carried into effect by reference to the accompanying drawing.

The shoe there shown consists of the following parts: the sole *a*, foxing *b*, vamp *c*, interposed sheet of rubber *d*, and lining *e*.

Before the shoe is put together I take the vamp *c*, and to its under side I attach, by means of cement or by passing the two between calender-rolls, a thin piece of rubber, *d*, which extends upon the upper to the height indicated by the line *x*. The lining *e* is bound to the vamp at its edge, but with this exception is entirely loose and unattached to the vamp throughout its whole extent. It will thus be seen, by reference to the drawing, that a space is left between the rubber *d* and vamp *c* and lining *e*, which enables the air to circulate freely through the upper and affords a passage for carrying off the insensible perspiration and moisture of the foot. The lining of the quarter *f* is made loose also for the same purpose. Instead of making the whole

surface of the vamp water-proof, I have found it best to attach the rubber to the vamp only to the extent indicated by the line *x*, this being ample for all practical purposes, while it increases materially the ventilation of the shoe.

The rubber sheet *d*, instead of being cemented or calendered to the vamp *c*, need not be attached thereto except at its lower edge, at the point where the vamp, lining, foxing, and rubber are secured to the sole *a*. This arrangement still further increases the ventilation, the air being free to circulate between the rubber *d* and vamp *c*, as well as between the rubber and the lining *e*, while, at the same time, the rubber still keeps off all external moisture from the foot. The upper thus constructed is secured to the other parts of the shoe by the method usually employed in the manufacture of this species of rubber shoe,

which method it is not deemed necessary here to describe.

Having thus described my invention, what I claim, and desire to secure by Letters Patent, is—

As a new article of manufacture, a rubber boot or shoe in which the upper is made water-proof and ventilating by interposing between the vamp and lining a sheet of rubber or water-proof fabric, which, whether attached or not to the vamp, leaves the lining loose, as and for the purposes set forth.

In testimony whereof I have signed my name to this specification before two subscribing witnesses.

JOHNSON LETSON.
